UNITED STATES PATENT OFFICE.

WILLIAM J. FOGARTY, OF DAYTON, OHIO.

DESIGN FOR A HOLDER FOR SIGNS.

Application filed May 28, 1921. Serial No. 473,409. Term of patent 7 years.

To all whom it may concern:

Be it known that I, WILLIAM J. FOGARTY, a citizen of the United States, residing at Dayton, in the county of Montgomery and State of Ohio, have invented a new, original, and ornamental Design for Holders for Signs, of which the following is a specification, reference being had to the accompanying drawing, forming part thereof.

The drawing shows a perspective and an

end view of my sign holder, showing my new design, and it is to be understood that signs composed of suitable thin material may be slipped into the groove at the upper and lower edge of the flat blank space.

I claim:

The ornamental design for a holder for signs, as shown.

WILLIAM J. FOGARTY.
